UNITED STATES PATENT OFFICE.

LLOYD SEESE, DECEASED, LATE OF NAVARRE, OHIO, BY ELIZABETH M. SEESE,
ADMINISTRATRIX, OF NAVARRE, OHIO.

AUTOMATIC TRAIN-STOP.

1,356,833.

specification of Letters Patent. Patented Oct. 26, 1920.

Application filed October 17, 1918. Serial No. 258,590.

To all whom it may concern:

Be it known that LLOYD SEESE, deceased, was during his life a citizen of the United States, and at the time of his death resided 5 at Navarre, in the county of Stark and State of Ohio, and that during his life he invented certain new and useful Improvements in Automatic Train-Stops; and I, ELIZABETH M. SEESE, administratrix of said LLOYD SEESE, residing at Navarre, in the county of Stark and State of Ohio, do hereby declare that the following is a full, clear, and exact description of the same, reference being had to the accompanying drawings, making a 15 part of this specification, and to the letters and figures of reference marked thereon.

This invention relates to automatic train stops and more particularly to this class of mechanisms designed for automatically stopping railroad locomotives, the object being to 20 arrange a mechanism of this class within the locomotive cab so that the train will be stopped should the engineer disregard the danger signal set against him.

With this object in view the invention 25 consists in the novel construction and arrangement of parts, hereinafter described, illustrated in the accompanying drawings, and particularly pointed out in the appended 30 claim, it being understood that various changes in the form, proportions, size and minor details of construction may be made within the scope of the appended claim, without departing from the spirit or sacrificing any of the advantages of the invention. 35

In the drawings:

Figure 1 is a fragmentary view of a railroad locomotive showing the cab, a portion of which is broken away to disclose the automatic train control mechanism.

Fig. 2 is a substantially diagrammatic front view of a locomotive passing a semaphore arm equipped with the train control contact member which is shown engaging 45 one of the contacts upon the locomotive cab.

Fig. 3 is a detail view of the automatic mechanism.

Similar numerals of reference indicate corresponding parts throughout the several 50 figures of the drawings.

At 1 is shown a locomotive cab upon either side of the roof of which is mounted a bracket 2, carrying a contact plate 3. Ribs 4 extend longitudinally of each of the contact 55 plates and parallel with the ribs 4 are

ribs 5 which are insulated from the plate 3 for a purpose to be hereinafter set forth. A circuit wire shown at 6 is connected to each of the plates 3 and a second wire 7 is connected to each of the series of ribs 5, the said wires extending thence downwardly and within the cab. A storage battery shown at 8 is located within the cab and is connected by circuit wires 9 and 10 with a solenoid 11. Extending from the core of the solenoid is a 60 hinged arm 12 which pivots to a pair of toggle arms 13 and 14, the arm 13 being hinged to a suitable base member within the cab and the arm 14 being hinged at its upper extremity to a contact block 15 carried by a 65 handle 16 connected to a valve 17 within an air line pipe 18. The contact block 15 is arranged to span the disjoined contacts of a switch located within the wire 10 and is arranged to close the said switch and allow the 70 current in the battery 8 to flow through the solenoid, thus drawing its core within it and pulling the arm 12 inwardly so that the arms 13 and 14 will be brought into vertical position. As long as current is flowing through 75 the solenoid the circuit to the solenoid will be held closed and the handle 16 of the valve 17, be kept in the position shown in Fig. 3, which position prevents the compressed air from flowing from the air tank shown at 19, 80 beyond the valve 17. A coil spring is shown at 20 attached at one end to the co-joined ends of the arms 12, 13 and 14, and at the other end to a suitable point of anchorage, such as the floor of the cab. The tendency 85 of the spring 20 will be to pull the arm 12 forwardly against the tendency of the solenoid. A similar spring 21 is attached to the arm 16 at one end and to a suitable point of anchorage at the other end, the tendency of 90 the spring 21 being to swing the arm 16 downwardly and open the valve 17 and break the circuit by moving the contact block 15 away from the contact points of the switch. 95

The pipe 18, as shown in Fig. 1, extends upwardly and enters one end of a cylinder 22 within which is located a sliding piston 23 and to the rod 24 of the said piston is pivotally connected the ordinary throttle lever 25 of the locomotive. A pipe 26 is tapped into the cylinder 22 at a point adjacent the end of the said cylinder in the end opposite the end at which the pipe 18 enters. The pipe 26 enters one end of a cylinder 27 to the rod of which piston is attached a valve 100 105 110

control handle 28 connected to the air brake control valve 29.

The circuit wire 6 leading from the plate 3 is tapped on to the wire 9 between the battery and solenoid and similarly the wire 7 is connected to the wire 10, but by reason of the fact that the ribs 5 to which the wire 7 is contacted are insulated from the plates 3 on which the wires 6 are contacted, no current normally flows through the wires 6 and 7, therefore leaving the circuit between the battery and the solenoid closed.

Referring now to Fig. 2, a semaphore standard shown at 30 of ordinary construction and carrying an ordinary semaphore arm 31 is shown. This semaphore is of the type commonly used at the entrance of each block on a railway system. An arm 32 extends at an angle outwardly from the semaphore arm 31 and upon the outer extremity of the arm 32 is mounted a comb member 33, which comb member carries a plurality of flexible contact fingers 34. The contact fingers are arranged in such a way that it will be impossible for the comb to pass over one of the series of contact plates carrying the ribs 5, without contacting with two or more of the ribs 4 and 5. It will be seen that should the semaphore arm be lowered to the position shown in full lines Fig. 2, the locomotive in passing the said semaphore arm will bring one of its contact members into alinement with the comb 33 and as it does so the flexible fingers 34 will wipe over a pair of ribs 4 and 5 and thus close the circuit through the wires 6 and 7 to the battery 8. As soon as the battery is short circuited by the contacting of the flexible fingers 34 with the contact ribs the current will cease to flow through the wires 9 and 10 to the solenoid, and the solenoid, being thus deenergized will release the core and the spring 20 will be free to exert a pull upon the arms 12, 13 and 14. As the arm 12 moves forwardly the arm 13, pivoted at its lower end will swing downwardly and the arm 14 will be pulled downwardly removing the contact block 15 from the points of the switch, thus breaking the circuit to the solenoid and at the same time swinging the handle 16 to open the valve 17 and allowing the compressed air to travel upward through the line 18 and to enter the cylinder 22. It is of course well known that when a locomotive is in operation the throttle is pulled outwardly and

the piston 23 would occupy a position at the opposite end of the cylinder 22 from that shown in the drawings. When, however, the air enters the cylinder 22 from the air line 18, the piston 23 will be moved backwardly toward the position shown in Fig. 1 and in passing the point of entrance the pipe 26 will allow the compressed air to escape into the cylinder 27 moving the piston within the said cylinder and rocking the handle 28 to the air brake control 29. It is obvious that as the piston 23 moves inwardly the throttle 25 will be drawn inwardly also and the steam line closed. Immediately upon shutting off the steam the air brakes are automatically operated and the train brought to a stand still.

Having fully described my invention what I claim as new and desire to secure by Letters Patent, is:

An electrically operated train control, including a solenoid and a circuit for supplying current to said solenoid constantly, a switch in said circuit, an arm pivoted to the core of said solenoid, a pair of links pivotally connected to said arm, the free extremity of one of said links being pivotally connected to a suitable stationary portion of the device, the free end of the other link being connected to said switch, a fluid line, a valve located in said fluid line, an arm upon said valve pivotally connected to the link to which the switch is connected, said valve being arranged to remain closed while the solenoid is energized, means for automatically moving said links to open said switch and open said valve when the solenoid is deenergized, cylinders in said fluid line, a throttle operatively connected to one of said cylinders, an air brake lever operatively connected to the other cylinder, a normally open circuit interposed between said solenoid and the source of power and designed to short circuit said first circuit, contact members connected to the terminals of said normally open circuit and a comb arranged to be engaged by said contact members to close said normally open circuit to deenergize said solenoid and cause the valve to be opened.

In testimony that I claim the above as administratrix of the estate of LLOYD SEESE, deceased, I have hereunto subscribed my name.

ELIZABETH M. SEESE,
Administratrix of Lloyd Seese, deceased.
